CLAIM

The ornamental design for a fluid mover enclosure, as shown
and described.

DESCRIPTION

FIG. 1 is a front perspective view of a fluid mover enclosure
showing our new design.

FIG. 2 is a top plan view of the fluid mover enclosure shown
in FIG. 1;

FIG. 3 is a bottom plan view of FIG. 1;

FIG. 4 is a front view of FIG. 1;

FIG. 5 is a back view of FIG. 1;

FIG. 6 is a right side view of FIG. 1;

FIG. 7 is a left side view of FIG. 1;

FIG. 8 is a front perspective view of the fluid mover
enclosure of FIG. 1, wherein the enclosure is shown
assembled within an environmental mounting; and,

FIG. 9 is a front perspective view of the fluid mover
enclosure of FIG. 1, showing the environmental mounting
exploded around the enclosure.

The dash-dot broken lines illustrate a boundary of the
claimed invention and form no part of the claimed design.
